MEANS TO DIMINISH SECONDARY
ELECTRON EMISSION

Gunther Jobst, Berlin, Germany, assignor to
Telefunken Gesellschaft für Drahtlose Tele-
graphie m. b. H., Berlin, Germany, a corpora-
tion of Germany

Application June 2, 1927, Serial No. 195,898.
Renewed December 28, 1933. In Germany June
4, 1926

7 Claims. (Cl. 250—27)

The object of the present invention is a form of construction or arrangement of a thermionic or electron tube so that the emission of secondary electrons by an electrode, for instance, the grid is reduced or completely suppressed.

It is a well-known fact that the grid in thermionic tubes emits electrons when operated at more than average potentials. If the grid potential is higher than, say 100 volts the electron emission 10 assumes rather considerable proportions. Such an emission of secondary electrons involves serious drawbacks in a number of uses of thermionic tubes. For instance, it may happen that, on account of marked emission of secondary electrons, 15 no current is flowing in the outer grid circuit since the direction of the secondary electron current is such that it opposes the primary electron current and just compensates or neutralizes the latter. The result is that what is known as grid 20 modulation telephony, which depends upon the action brought upon the grid and the current flowing therein, becomes impracticable. Another drawback is that on account of secondary electron emission, the production of waves is prevented or 25 that undesired or spurious oscillations are generated. Now, the purpose of the present invention is to provide ways and means whereby appreciable electron emission from the grid is pre- 30 cluded, this being accomplished by the influence of the positive plate potential on the grid, which causes an attraction of the secondary electrons with the result that a secondary electron current 35 if caused, is prevented.

According to the disclosures of this invention, 35 a conducting body, for instance, in the form of a cage surrounding the grid or else a separate protective grid is provided in close proximity to the main grid, said cage or protective grid being kept at a lower potential or at the same potential 40 as the filament or cathode. One embodiment of the basic idea of the invention consists in an arrangement such that between the control grid and the plate, an additional grid is disposed which is connected directly with the filament so that 45 it is kept at the same potential as the latter.

In the drawing, Fig. 1 is a diagrammatic view 50 of the arrangement of the tube elements.

Fig. 2 shows a diagrammatic tube arrangement 55 with a modified form of auxiliary grid.

Fig. 3 is a partial section of a tube embodying 60 my invention.

Fig. 4 is a plan view of Fig. 3.

Fig. 5 shows diagrammatically suitable circuits 65 connected to the elements of the tube, and

Fig. 6 shows a modified form of the tube in Fig. 5.

A form of construction as before outlined is dia- 60 grammatically illustrated in Fig. 1 showing a sec- 65 tion through the axis of the electrode arrange- 70 ment of a thermionic tube. F denotes the fila- 75 ment, G the control grid, P the plate, while the auxiliary grid H is arranged between the control 80 grid G and the plate P, said auxiliary grid being connected directly with the filament by a conduct- 85 ing connection I. It will be understood that the latter connection may be provided either inside 90 the tube as shown in Fig. 6, in which case the construction of the tube must be conveniently chosen, or else outside the tube. The auxiliary grid may be of annular, rod or wound (helical) 95 form.

Another form of construction is illustrated in 70 Fig. 2. In this scheme, the grid is surrounded 75 partly by a conducting cage K which is also con- 80 nected directly with the filament. However, it has been found to be necessary to envelop only 85 about $\frac{1}{6}$ of the length of the grid by the said cage.

In the tube shown in Figs. 3 and 4 the fila- 80 ment is mounted centrally and surrounding this 85 is the control grid G made of wire into a gener- 90 ally cylindrical form. Close to this grid and surrounding it is the auxiliary grid H made into cylindrical form by a helically wound wire. The plate P may be of any desired shape, that shown 95 being cylindrical, but plates of other form may be used instead.

Fig. 5 shows a circuit arrangement using a tube of this form in which the plate voltage is about 200 volts and that of the main grid about 100 volts, this voltage being supplied by a bat- 90 tery or other source of direct current A. The filament current is supplied by battery B and a sliding contact C connected to the auxiliary grid H adjustably engages this battery, whereby volt- 95 age of grid H may be made equal to or lower than that of the filament.

In Fig. 6 there is shown a modification of the connection between the cathode F and the auxil- 100 iary control electrode H, as shown in Fig. 5, wherein the connection I is disposed within the envelope E, the connection being directly be- 105 tween the electrode H and the cathode F. It is to be understood that the remaining connec- 110 tions of Fig. 6 are similar to those shown in Fig. 5.

While the method and arrangement above de- 110 scribed for decreasing or preventing the emis- 115 sion of secondary electrons has been described as applied to the control grid, I do not limit myself to this particular electrode as the auxiliary

grid may evidently be used in conjunction with the plate or other electrode of a vacuum tube to prevent emission of secondary electrons therefrom.

5 Having described my invention and the means which at present I consider preferable for carrying it into effect, it will be understood that I do not limit myself to the means shown but wish to include within the scope of my invention 10 any method and means within the scope of the following claims.

I claim:

1. In a vacuum tube having a source of electrons, a grid, and a plate, an output circuit connected to said grid and plate, means interposed between the grid and plate and spaced from said grid to prevent secondary electrons emitted by the grid due to impact by said first named electrons from moving toward the plate, said means being so constructed that said first electrons reach said plate, and means for maintaining said grid positively charged with respect to the cathode.

2. In an electron discharge tube circuit of the type including a tube provided with a cathode, a highly positive cold electrode, and at least one additional positive cold electrode intermediate the cathode and the first cold electrode, an output circuit to which both the cold electrodes are connected, means for maintaining the said first cold electrode at a positive potential of the order of 200 volts with respect to the cathode, and a grid, connected within the tube to the cathode, disposed between the two cold electrodes for establishing a negative potential field with respect to the cold electrodes to suppress the flow of secondary electrons from one of said cold electrodes in the direction of the other cold electrode.

3. In an electron discharge tube circuit of the type including a tube provided with a cathode, a highly positive cold electrode, and at least one additional positive cold electrode intermediate the cathode and the first cold electrode, an output circuit to which both the cold electrodes are connected, means for applying high positive potentials to said cold electrode of such magnitude with respect to the cathode that emission of secondary electrons from at least one of the cold electrodes by impact therewith, and a grid, connected within the tube to the cathode, disposed between the two cold electrodes for establishing a negative potential field with respect to the cold electrodes to suppress the flow of said secondary electrons from said one cold electrode in the direction of the other cold electrode.

4. In an electron discharge tube circuit of the type including a tube provided with a cathode, a highly positive cold electrode, and at least one additional positive cold electrode intermediate the cathode and the first cold electrode, an output circuit to which both the cold electrodes are connected, means for maintaining the said first cold electrode at a positive potential of the order of 200 volts and the additional cold electrode at a positive potential of the order of 100 volts with respect to the cathode, and a grid, connected within the tube to the cathode, disposed between the two cold electrodes for establishing a negative potential field with respect to the cold electrodes to suppress the flow of secondary electrons from one of said cold electrodes in the direction of the other cold electrode.

5. An electron discharge tube comprising a cathode for emitting primary electrons, a grid electrode and a plate electrode surrounding said cathode, and means for preventing the flow of secondary electrons between said grid and plate electrodes due to primary electron impact thereagainst comprising a conducting cage member which only partly surrounds the grid electrode 100 and is directly connected to the cathode.

6. An electron discharge tube comprising a cathode for emitting primary electrons, a grid electrode and a plate electrode surrounding said cathode, and means for preventing the flow of 105 secondary electrons between said grid and plate electrodes due to primary electron impact thereagainst comprising a conducting cup-shaped member disposed at one end of the electrodes and having a portion extending only partly within the space between grid and plate, said cup-shaped member being electrically connected to the cathode.

7. An electron discharge tube comprising a cathode for emitting primary electrons, a plate 115 electrode at a comparatively high potential surrounding the cathode for collecting the primary electrons, a grid electrode interposed between cathode and plate and maintained at a lower positive potential than the plate, and means for 120 preventing secondary electron emission from grid and plate due to primary electron impact thereagainst comprising a transverse member extending over one end of the grid and connected to the cathode, said member having an 125 annular portion which extends only partly into the space between grid and plate.
